UNITED STATES PATENT OFFICE.

CHARLES A. BAILEY, OF CROMWELL, CONNECTICUT.

PIPE-THREADING IMPLEMENT.

SPECIFICATION forming part of Letters Patent No. 598,279, dated February 1, 1898.

Application filed October 8, 1897. Serial No. 654,566. (No model.)

To all whom it may concern:

Be it known that I, CHARLES A. BAILEY, a citizen of the United States of America, residing at Cromwell, in the county of Middlesex and State of Connecticut, have invented certain new and useful Improvements in Pipe- Threading Implements; and I do hereby declare the following to be a full, clear, and exact description of the invention, such as will enable others skilled in the art to which it appertains to make and use the same.

This invention is an improved implement for threading soft-metal pipe, the object of the same being to provide an implement of this character which is simple and cheap in construction and also possesses the more important advantage of being quickly and easily operated in forming the threads.

The invention contemplates a construction and arrangement of parts by which the ribbed swaging-roll can be readily and conveniently removed and another substituted to adapt the device for forming right and left hand threads as well as threads of different sizes.

To the above ends and to such others as the invention may pertain the same consists, primarily, of a lever revolved around the pipe and a swaging-roll carried by the lever, said swaging-roll having a spiral rib, together with a plug inserted within the end of the pipe.

The invention further consists in the combination of the plug having a spindle, a lever rotatably mounted on said spindle, and a swaging-roll carried by the lever, the swaging-roll being provided with a spiral rib that forms the thread upon the pipe.

The invention further consists of a lever revolved around the pipe, a swaging-roll removably attached to the lever, said roll having a spiral rib, and means for adjusting the roll to and from the pipe, together with a plug fitting within the end of the pipe.

The invention further consists in the particular construction and combination of the parts comprising the complete implement, as fully described in the following specification and more specifically set forth in the appended claims.

In the accompanying drawings, which form a part of this specification, Figure 1 is a side elevation of a pipe-threading implement con-

structed in accordance with my invention, the position of the pipe being shown in dotted lines. Fig. 2 is a vertical longitudinal sectional view. Fig. 3 is a transverse sectional view through the handle of the operating-lever. Fig. 4 is a detail perspective view of the swaging-roll and carrier therefor.

Referring more particularly to said drawings, A designates a plug which is of a size to fit snugly within a pipe having a bore of a corresponding size, and extending from this plug is a spindle a, forming a bearing or axle for the operating-lever hereinafter described, the outer end of said spindle being threaded to receive a cap-nut B, which limits the movement of the lever upon the spindle and also serves to intimately connect these parts. The plug, with its spindle, provides a support for the operating-lever, and the plug proper also serves as a core in the end of the pipe to prevent said pipe being crushed in during the operation of forming the threads on the outer side thereof. The surface of the plug is plain, though, if desired, it may be provided with longitudinal serrations to insure a better engagement with the inner side of the pipe. It is apparent that I contemplate supplying the implement with plugs of different sizes for use in connection with different sizes of pipes.

The operating-lever (designated by the letter C) presents a curved arm c, extending from a handle c', the latter having a longitudinal bore through the same, while the arm is provided with an opening through which passes the spindle a, hereinbefore referred to. The bore is threaded a suitable distance beginning at the outer end of the handle c', the other portion being smooth to receive the shank d of a carrier D, presenting a yoke d', within which is mounted a swaging roll or cylinder F upon an axle e, bearing at its ends in said yoke. Upon the surface of said roll or cylinder is formed a spiral rib f, presenting a rotary die adapted when moved around a pipe to form a thread thereon of a certain size and pitch. To form a thread of a different size, said swaging-roll is removed and another substituted either by withdrawing the axle e or the carrier with its roll. The shank of the carrier D is provided with a lon-

itudinal groove d^2 , into which projects the end of a set-screw G, that is passed through a threaded opening therefor in the handle of the operating-lever, the screw serving to prevent a rotary movement of the carrier, while the groove permits of a longitudinal feed, this feeding movement being provided for by an adjusting-screw H, let into the threaded portion of the bore of the handle and preferably provided with a milled head. It will be understood that the set-screw G does not engage the shank of the carrier to the extent of interfering with the proper feed of the latter during the operation of forming a thread, but merely serves to prevent rotation of said carrier. It will also be understood that this could be provided for by forming that part of the bore with which the shank of the carrier engages rectangular in shape, with the shank to correspond.

From the foregoing description, in connection with the accompanying drawings, the construction and operation of my improved pipe-threading implement will be readily understood, for after driving the plug A into the end of the pipe the lever C is moved along the spindle and the adjusting-screw H turned to bring the swaging-roll against the pipe, embedding the rib therein. The lever being then turned around the pipe will cause said swaging-roll to rotate and impress or rule the thread. It is apparent that a swaging-roll having a right-hand thread or rib thereon will form a left-hand thread on the pipe, and vice versa. Therefore either style of thread can be formed by inserting the proper swaging-roll into the implement.

It is obvious that modifications could be made in the implement and parts thereof in addition to those hereinbefore mentioned, and I therefore declare that I do not wish to confine my protection by patent to what is herein precisely shown and described, but desire to reserve the right to change the construction and arrangement of parts within the spirit and scope of my claims.

Having thus described my invention, what I claim as new, and desire to secure by Letters Patent, is—

50. 1. An implement for threading pipe, comprising a lever revolved around the pipe, and a swaging-roll carried by the lever, said swag-

ing-roll having a spiral rib thereon; together with a plug or core fitting within the pipe.

2. In an implement for threading pipe, the combination of a plug or core fitting within the pipe and presenting a spindle, a lever rotatably mounted on said spindle, and a swaging-roll carried by said lever, the swaging-roll having a spiral rib thereon, substantially as shown and described.

3. In an implement for threading pipe, the combination of a plug, a spindle extending therefrom, a cap-nut screwed on the end of the spindle, and a lever mounted on the spindle below the nut; together with a swaging-roll carried by the lever and provided with a spiral rib, substantially as shown and described.

4. In an implement for threading pipe, the combination of a plug, a spindle extending therefrom, a lever mounted on the spindle, a carrier detachably connected to the lever, and means for setting said carrier; together with a swaging-roll mounted within the carrier and provided with a spiral rib thereon, substantially as shown and for the purpose set forth.

5. In an implement for threading pipe, the combination of a plug, a spindle extending therefrom, a lever mounted on the spindle, a carrier having a movement within the lever, a screw engaging a threaded opening in the lever and bearing against said carrier; together with a swaging-roll mounted within the carrier and provided with a spiral rib, substantially as shown and described.

6. In an implement for threading pipe, the combination of a plug having a spindle, a lever mounted to rotate thereon and presenting a curved arm and hollow handle, a yoked carrier let into the hollow handle at one end thereof, a screw let into the other end of said handle to bear against said carrier, means for preventing a rotary movement of the carrier, and a swaging-roll mounted within the carrier and provided with a spiral rib, substantially as shown and described.

In testimony whereof I affix my signature in presence of two witnesses.

CHAS. A. BAILEY.
